(57) **CLAIM**

I claim the ornamental design for an shelving system,
substantially as shown and described.

DESCRIPTION

FIG. 1 is a top, left perspective view of the shelving system
in an environment of use.

FIG. 2 is a top, right perspective view of the shelving system
in an alternate environment of use.

FIG. 3 is a top, perspective view thereof;

FIG. 4 is a front elevation view thereof;

FIG. 5 is a rear elevation view thereof;

FIG. 6 is a side elevation view thereof;

FIG. 7 is a side elevation view thereof;

FIG. 8 is a top view thereof;

FIG. 9 is a bottom view thereof; and,

FIG. 10 is a bottom, perspective view thereof.

A description of the appearance of the article is as follows:
An shelving system. The broken lines showing portions of
the design in the figures are included for the purpose of
illustrating environment and unclaimed features and forms
not part of the claimed design.

1 Claim, 10 Drawing Sheets
